United States Patent Office.

JOHN GIBBS, OF BROOKLYN, E. D., NEW YORK, ASSIGNOR TO HIMSELF AND
CALVIN H. CARTER, OF WATERBURY, CONNECTICUT.

Letters Patent No. 99,309, dated February 1, 1870.

IMPROVED PUNCH AND DIE FOR PUNCHING TUBES.

Schedule referred to in these Letters Patent and making part of the same

To all whom it may concern:

Be it known that I, JOHN GIBBS, of Brooklyn, E. D., in the county of Kings, and State of New York, have invented a new and useful Improvement in Cutting Slots in Metallic Tubes; and I do hereby declare that the following is a full, clear, and exact description thereof, which will enable others skilled in the art to make and use the same, reference being had to the accompanying drawings, forming a part of this specification.

This invention relates to a new and useful improvement in method of cutting slots in metal tubes, having more particular reference to the tubes or safes employed in the use of the "endless match," and consists in the use of a die and punch in combination, with a partition-bed and mandrel for making longitudinal slots or recesses in one or both sides of the tube, for giving access to the match used, but which method of cutting slots is applicable to tubes used for other purposes.

In the accompanying drawing—

Figure 1 is a top view of the die, partly in section, showing the tube as completed.

Figure 2 is a vertical section of the punch and die through the line *xx* of fig. 1.

Figure 3 represents a sectional top view of the die without the tube.

Similar letters of reference indicate corresponding parts.

A is the die, which is properly secured on the bed of the press, having an aperture through it, divided by the vertical partition *B*, and supporting a horizontal mandrel, *C*, by means of a fastening plate, *D*.

This mandrel is placed directly over the partition *B*, and its gauge or diameter is equal with the thickness of *B*. The space between the mandrel and the partition *B* is designed to be about equal to the thick-

ness of the tube-metal, but the mandrel is allowed some play, to compensate for the variations in the thickness of the metal of the tube. The mandrel fits the tube, but is flattened on its sides, so that at the slot it only fits the tube at its upper and under sides.

The tube *E* is shoved on to the mandrel, and its forward end enters a hole in the fastening-plate *D*, as seen in fig. 1, while its back portion is supported by the die-plate, as seen in same figure.

When thus placed, the tube is ready for the punch, and when the punch descends, pieces are cut from its sides through the tube-metal, making slots in the tube, and leaving the tube as seen in fig. 1.

F is the punch, which is worked vertically by foot, or otherwise, the slot *g* in it being equal to the thickness of the mandrel *C*, and the partition *B*. Its inner corners are cutting-edges, as are the upper angles of the flattened portion of the mandrel *C*, and upper angles of the partition *B*.

By widening the slot *g* in the punch, and flattening only one side of the mandrel, a single instead of a double slot may be cut in the tube, should a single slot be required in tubes for any purpose.

By this arrangement, slots in tubes may be cut of any desired size and shape with the greatest accuracy and expedition.

Having thus described my invention, what I claim as new, and desire to secure by Letters Patent, is—

In combination with the die *A*, partition *B*, and mandrel *C*, the punch *F*, all arranged and operating substantially as herein shown and described and for the purpose set forth.

JOHN GIBBS.
